RAIL CAR

Raymond M. Shaver, Michigan City, Ind., assignor
to Pullman-Standard Car Manufacturing Com-
pany, Chicago, Ill., a corporation of Delaware

Application May 2, 1941, Serial No. 391,449

9 Claims. (Cl. 105—410)

The present invention has to do with the end wall and corner post condition of a railroad box car. It is intended to simplify and improve prior existing structures, and that is the principal object of this invention.

In steel box cars, it is common practice to employ wood liners on the inner faces of the end and side walls. Wood nailing strips are disposed on the inner faces of the metal sheathing to which the lining is nailed. Rivets are commonly employed in the construction of steel freight cars, and consequently rivet heads appear on the inner faces of the metal sides and ends. In the past, it has been necessary to notch out the liner boards in order to fit them over these rivet heads. The present invention in a simple and inexpensive manner very effectively makes it possible to dispense with this notching operation.

In certain types of constructions, it has been impossible to extend the nailing strips throughout the entire width of the car end wall, because of obstructions occurring in the region of the corner posts. The structure forming the subject matter of the present invention makes it possible to extend these nailing strips throughout the entire width of the end wall, thereby making it possible to completely anchor the boards making up the end lining.

The above constitute some of the principal objects and advantages of the present invention, others of which will become apparent from the following description and drawings, in which

Fig. 1 is a diagrammatic longitudinal vertical sectional view through a car showing the end portion only thereof;

Fig. 2 is an enlarged fragmentary perspective view of one corner of the car showing the corner post and corner conditions;

Fig. 3 is an enlarged horizontal sectional view taken on the line 3—3 of Fig. 1;

Fig. 4 is an enlarged horizontal sectional view taken on the line 4—4 of Fig. 1;

Fig. 5 is an enlarged vertical sectional view taken on the line 5—5 of Fig. 4;

Fig. 6 is a fragmentary perspective view of one corner of the car showing a modified corner condition;

Fig. 7 is a horizontal sectional view through the car corner shown in Fig. 6, the figure being taken in the region between the corrugations;

Fig. 8 is a horizontal sectional view corresponding to Fig. 7 with the view being taken through one of the corrugations;

Fig. 9 is a horizontal sectional view through a

corner of the car showing a modified arrangement, the view being taken in the region between corrugations; and

Fig. 10 is a horizontal sectional view corresponding to Fig. 9 with the view being taken through one of the corrugations.

For the purpose of complying with section 4883 of the Revised Statutes specific embodiments of the present invention have been selected for making the disclosure. Obviously many modifications may be made without departing from the scope of the invention.

Referring to Fig. 1, the invention is shown as it relates to a box car having an end wall 20, a pair of side walls one of which is shown at 21 in Fig. 2, a roof 23 (Fig. 1) and an underframe generally indicated at 24. An end sill 25 forms part of the underframe 24 and serves as a means for connecting the end wall 20 to the underframe.

The end wall 20 is provided with a plurality of corrugations 26 which extend horizontally, and, as best shown in Fig. 3, these corrugations taper toward the corners of the car and extend around the end at 27 and flatten out into a flange 28. The car side 21 is made up of flat sheets, one of which is shown at 29 in Fig. 3.

At the corner of the car is a corner post 30, which may be made up of a central web portion bent to form segments 31 and 31' and a pair of flanges 32 and 33, the former of which extends parallel to the car side 21 and the latter of which extends parallel to the general plane of the end wall 20. As shown in Fig. 3, this post is in the shape of a W in horizontal section.

The side wall 21 and the flange 28 of the end wall 20 and the flange 32 of the W corner post are all fastened together by means of rivets 34, the side sheet 29 being sandwiched in between the flange 28 of the end wall 20 and the flange 32 of the W corner post.

The flange 33 of the W corner post may be secured to the end wall 20 by means of rivets 35 (Fig. 4).

Secured to the web portion 31' of the corner post is a vertically extending nailing strip 36 by means of bolts 37 having nuts 38 threaded onto their shanks. Washers 39 may be interposed between the nuts 38 and the nailing strip 36.

The side and end walls of the car on the interior thereof are lined with wooden liners 40 and 41 respectively. The side wall liners 40 are secured to nailing strips 36 and they extend toward the end 20 of the car against the inner face of the portion 31 of the corner post web.

The end liner 41 is made up of a plurality of wooden strips 41' joined at 42. This end liner extends between the oppositely disposed side liners 40, and terminates against these side liners as best shown in Fig. 3. A plurality of nailing strips 44 (Figs. 3 and 5) are provided in the corrugations of the end wall, and these strips are suitably secured to the end wall by means of bolts 45 (Fig. 1). The inner faces of these liners are countersunk at 46, so that the nuts 45' on the end of the bolts 45 are recessed in the nailing strips. The end liner 41 is held in place against the end wall of the car by means of nails 47 (Fig. 3), which are driven into the nailing strips 44.

Heretofore, the nailing strips 44 have been prevented from extending to the extreme end of the end liners 41 because of the obstruction created by flange 33 of the corner post. The present invention overcomes this difficulty by coping out the flange 33 at 48, so as to receive the nailing strip 44. This coping out is done at suitable places along the length of the flange 33, so as to accommodate the numerous nailing strips 44. Thus, as clearly shown in Fig. 3, the nailing strip 44 extends to the very end of the end liner 41, and thus it has been made possible to nail the liner in place throughout its entire width.

As shown in Fig. 2, the end strip 41' of the end wall liner 41 is notched out at 49, so as to clear the portions 33' of the corner post flange 33, which is not coped out, and thus a plurality of solid portions 50 are provided along the inner face of the end strip 41', which fit into the coped out slots 48 of the flange 33 and against the nailing strips 44. In this manner, the end wall liner 41 is rigidly supported by the nailing strip 44 throughout its entire width, a condition which previously had not been possible to attain. As best shown in Figs. 4 and 5, the liner 41 was notched out at 51 to provide clearance for the heads 52 of the rivets 35.

Referring now to Fig. 6, a somewhat modified condition is shown. The end wall is here shown at 53, and it is provided with an outwardly offset vertical portion 54 (Figs. 6 and 7). The end wall liner 41, as previously described, is disposed against the face of the end wall, so that in the region of this offset portion 54 the end liner 41 is spaced inwardly with respect to this offset portion. Thus, in the region of this offset portion there is a space between the car end wall and the liner 41 sufficient in depth to provide clearance for the rivet head 52 (Fig. 7). In this manner, it is possible to dispense with the necessity of notching out the liner 41 to provide clearance for the rivet head 52. As shown in Fig. 6, the nailing strips 44 extend into the coped out slots 48 in the flange 33 of the corner post, so that here, again, this nailing strip extends to the extreme end of the liner 41 (Fig. 8).

It may be desirable to countersink the inner rivet head, as shown in Fig. 9 at 55. If this is done, the degree of offsetting of the end wall does not need to be as great, so that in this case the offset portion 56 is more nearly in the general plane of the car end wall. If the rivet head 55 is countersunk and flat, as shown in Fig. 9, the end wall liner 41 may be laid flush against the inner face of the corner post flange 33, and, as previously described, the nailing strips 44 will back the end wall liner 41 throughout its entire width as shown in Fig. 10.

In the various forms of the invention disclosed herein, the corner post is shown as being in the

form of a W in cross section. Obviously this condition can be changed, and, instead, the web portion of the W can be straightened out to form a straight diagonal between the car side and end walls. Also, in some of the figures herein the end wall is curved as it passes from the general plane of the end wall to the side wall. Obviously, this condition can be changed and other forms may be employed, such as a substantially square corner, as shown in Figs. 9 and 10.

By eliminating the necessity of notching out the end wall liner to clear rivet heads and the like, the construction of this portion of the car is greatly simplified. Also, the provision making possible the extension of the nailing strips to the very ends of the liner makes for more rigid construction of the liner.

1. In a railway box car, a side wall and a corrugated end wall, a corner post having flanges disposed inside the side and end walls and extending parallel to the side and end walls respectively and secured thereto, wooden liners on the inside of the car disposed parallel respectively to the car side and end walls, and nailing strips secured to the end wall and disposed in certain of the corrugations between the end liner and the end wall, the flange of the corner post adjacent to the end wall being notched out to receive the nailing strips so that the strips can extend throughout the full width of the end liner.

2. In a railway car, a side wall, a horizontally corrugated end wall, a corner post comprising a generally diagonal brace between the car side and end walls, and flanges extending parallel respectively to the car side and end walls, means for fastening the flanges respectively to the side and end walls, an end liner on the inside of the car end wall overlapping the flange of the corner post adjacent to the car end wall, and a nailing strip between the liner and the end wall and disposed in one of the horizontal corrugations in the end wall, the flange of the corner post being slotted to receive the nailing strip, the nailing strip extending into said slot and to the extreme end of the liner.

3. In a railway car, a side wall, an end wall, a corner post comprising a generally diagonal portion between the side and end walls and flanges disposed parallel respectively to the side and end walls, the end wall comprising a vertical portion offset outwardly with respect to the general plane of the car end wall, said offset portion being adjacent to the corner post flange paralleling the end wall so that the flange engages the end wall in this offset portion, means for securing the last named flange to the offset portion of the end wall, an end wall liner on the inner face of the car end wall and adapted to project over the offset portion of the end wall and being spaced from said offset portion, and means for securing the liner to the end wall.

4. In a railway box car, a car side wall, an end wall, a corner post having a flange parallel to the end wall for securing the post to the end wall, the portion of the end wall adjacent to the post flange being offset outwardly an amount not less than the thickness of the flange and accommodating the said flange, means for securing the flange to the offset portion of the end wall, and an end wall liner overlapping the said corner post flange.

5. In a railway box car, a car side wall, a horizontally corrugated end wall, a corner post having a flange parallel to and disposed inside and against the end wall, the portion of the end wall

adjacent to the post flange being offset outwardly an amount not less than the thickness of the flange, means for securing the flange to the offset portion of the end wall, an end wall liner against the inner face of the end wall and projecting over the flange of the corner post, and a nailing strip in one of the horizontal corrugations between the end wall and the end liner, the flange of the corner post being coped out to receive the nailing strip so that said strip can extend to the extreme edge of the end liner.

6. In a railway car, a side wall, a horizontally corrugated end wall, a corner post including a generally diagonal brace disposed between the side and end walls and having a flange extending parallel to and along the inner face of the end wall, means for securing the said flange to the end wall, an end liner on the inside of the car end wall lining substantially the entire end wall area, and a nailing strip between the liner and the end wall disposed in one of the horizontal corrugations in the end wall, the flange of the corner post being removed from the path of the nailing strip, the nailing strip being at least coextensive with the length of the end liner and being disposed against the liner throughout the length of the liner so that the liner throughout its length can be secured to the nailing strip.

7. In a railway car, a side wall, a horizontally corrugated end wall, a corner post including a generally diagonal brace disposed between the side and end walls and having a flange extending parallel to and along the inner face of the end wall, means for securing the said flange to the end wall, an end liner on the inside of the car end wall comprising a plurality of vertically disposed boards interconnected to present a flush surface on the inside of the car and lining substantially the entire end wall area, and a nailing

strip between the liner and the end wall disposed in one of the horizontal corrugations in the end wall and against the boards making up the liner, the flange of the corner post being removed from the path of the nailing strip, the nailing strip being at least substantially coextensive with the length of the end liner so as to back up all of the liner boards including substantially all of the one disposed nearest to the corner post.

10. 8. In a railway car, a side wall, a horizontally corrugated end wall, a corner post including an angular member having a flange disposed substantially parallel to the end wall and fastened to the end wall and forming therewith a box

15. column, an end liner on the inside of the car end wall lining substantially the entire end wall area, and a nailing strip between the liner and the end wall disposed in one of the horizontal corrugations in the end wall, the flange of the angular

20. member being notched so that the said nailing strip can extend without obstruction throughout the full length of the said liner so that the liner throughout its length can be secured to the nailing strip.

9. In a railway car, a side wall, a horizontally corrugated end wall, a corner post including a generally diagonal brace extending between the car side and end walls and having a flange disposed substantially parallel to the end wall, an end liner on the inside of the car end wall lining

30. substantially the entire end wall area, the said flange being notched, and a nailing strip between the liner and the end wall disposed in one of the horizontal corrugations in the end wall and being at least coextensive with the length of the end liner and fitting into the notches so that the liner throughout its length can be secured to the nailing strip.

RAYMOND M. SHAVER.
